US0D1087437S

(12) **United States Design Patent** (10) Patent No.: **US D1,087,437 S**
(45) Date of Patent: ** Aug. 5, 2025

(54) **AMBIENT PROJECTION LIGHT**

(71) Applicants: **Jiangxi Huasu Electronics Co., Ltd.**,
Jiangxi (CN); **Shenzhen Jutian Lianchuang Technology Co., Ltd.**,
Guangdong (CN); **Jiangxi Blue Label Technology Co., Ltd.**, Jiangxi (CN);
Xingan County Baiyi Technology Co., Ltd., Jiangxi (CN);
Xingan County Yixing Electronics Co., Ltd., Jiangxi (CN);
Xingan County Yineng Electronics Co., Ltd., Jiangxi (CN);
Jiangxi Haidi Electronic Technology Co., Ltd., Jiangxi (CN)

(72) Inventors: **Qinghui Liu**, Jiangxi (CN); **Xiaoliang Ruan**, Jiangxi (CN)

(**) Term: **15 Years**

(21) Appl. No.: **29/980,289**

(22) Filed: **Dec. 23, 2024**

(51) LOC (15) Cl. **26-05**

(52) U.S. Cl.

USPC **D26/93**; D26/110

(57) **CLAIM**

The ornamental design for an ambient projection light as shown and described.

DESCRIPTION

FIG. 1 is a perspective view of an ambient projection light showing our new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the ambient projection light and form no part of the claimed design.

1 Claim, 8 Drawing Sheets
